DISPOSABLE INFUSION SET

Silas S. Smith, Jr., Bountiful, Utah, assignor to Desert Pharmaceutical Company, Inc.

Filed Feb. 6, 1967, Ser. No. 5,706

Term of patent 14 years

(Cl. D83—12)

FIG. 1

FIG. 2

FIG. 5

FIG. 3

FIG. 6

FIG. 4

FIG. 1 is a perspective view of a disposable infusion set, embodying my new design;

FIG. 2 is an enlarged perspective view of the inserter and needle assembly, the broken line portions have been omitted for ease of illustration;

FIG. 3 is a top plan view thereof;

FIG. 4 is a bottom plan view thereof.

FIG. 5 is a front elevation thereof; and

FIG. 6 is a bottom view thereof.

The dominant features of my design reside in the portions shown in full lines.

I claim:

The ornamental design for a disposable infusion set, substantially as shown and described.
